C. J. WOTIER

VALVE FOR POWDER DISTRIBUTORS

Filed Oct. 1, 1920

Inventor

C. J. Wotier

Lacy & Lacy, Attorneys

UNITED STATES PATENT OFFICE.

CHARLES J. WOTIER, OF SPRINGFIELD, TENNESSEE.

VALVE FOR POWDER DISTRIBUTORS.

Application filed October 1, 1920. Serial No. 413,959.

To all whom it may concern:

Be it known that I, CHARLES J. WOTIER, citizen of the United States, residing at Springfield, in the county of Robertson and State of Tennessee, have invented certain new and useful Improvements in Valves for Powder Distributors, of which the following is a specification.

This invention relates to improvements in valves for dispensing devices or distributors especially adapted for use in spraying insecticides and fungicides and the like on to plants, shrubs, trees, etc.

The invention forming the subject matter of this application aims to provide a powder distributor of the class described having a simple valve arrangement adapted for regulating the discharge of the powder from the valves of the same.

20 A further object of the invention is to provide a device of the class described which is simple to operate, durable in use and cheap to manufacture.

Other objects and advantages of the invention will be apparent during the course 25 of the following description.

In the accompanying drawings, forming a part of this application and in which like numerals are employed to designate like parts throughout the same;

Figure 1 is a side elevation of the improved powder distributor in use.

Figure 2 is a vertical detail sectional view through the reservoir and one of the valves,

35 Figure 3 is a vertical detail sectional view taken on line 3—3 of Figure 2.

Figure 4 is a perspective view of a valve embodied in the invention.

In order that the valve and its use may 40 be fully and readily understood, I have shown a powder distributor and will describe some of its essential features of construction and operation.

In the drawings, the numeral 15 designates a cylindrical blower which may have a plurality of fan-containing compartments. Air is taken into the compartments through openings 29 formed in the central portions of the side walls of the blower. The end portions of the fan shaft are fitted through openings in the intermediate portions of straps 30 which extend across the openings 29 and are secured to the sides of the blower by means of rivets 34 or other suitable 55 fastening devices.

With reference to Fig. 2, it will be ob-

served that a shaft 44 is extended through the lower portion of a reservoir 47, and suitable means for rotating said shaft and the fan shaft is, of course, provided.

It might be stated that the reservoir 47 is adapted to contain a powder which it is desired to spray over rows of plants, shrubs, bushes, or trees, for destroying either fungus or insects. The powder is introduced into the reservoir 47 through an opening which is normally closed by means of a cap. The reservoir, which is arranged in advance of the blower, is provided in its under side with an opening or openings 56 which permit the discharge of the powder into discharge members 58 of tubular formation. The rear portions of the discharge tubes 58 are enlarged as indicated at 59 and communicate with the lower portions of the fan 75 compartments. Therefore, upon the rotation of the fans within the blower, a blast of air is created which is directed through the enlarged portions 59 of the discharge tubes 58 so that a quantity of powder is drawn through the openings 56 into the discharge tubes.

With reference to Fig. 2 it will be observed that brushes 60 are keyed or otherwise secured to the shaft 44 within the reservoir 47 and are rotated during the operation of the device so as to agitate the powder whereby the powder is caused to pass through the discharge openings 56 uniformly. The brushes 60 are arranged directly above the openings 56 and therefore efficiently direct the powder through the openings in addition to thoroughly agitating the same. The discharge members are provided with openings 64 which are aligned with the openings 56 so as to allow the powder to readily enter the discharge members. However, each discharge member is provided with a sleeve valve 66 having one side provided with an elongated opening 68 which is adapted to be aligned with the openings 64 and 56. When the sleeve valve is partially rotated by means of the adjusting member or lug 70 the opening 68 may be brought out of registration with the opening 64 so as to cut off communication between the reservoir and the discharge member. When it is desired to merely reduce the flow of powder from the reservoir, the opening 68 may be brought only partly out of registration with the opening 64 in the member 58. The handle 70 of each

sleeve valve 66 is arranged within an ar-
cuate slot 72 in the lower portion of the
discharge member 58. In the use of the
device, the sleeve valve is securely held in
position by means of the handle 70 and as
the ends of the sleeve valve are entirely
open, the powder may readily flow through
the same. When open, the sleeve valve does
not in any way interfere with the passage of
the powder or the air through the discharge
member 58. The sleeve valve is, of course,
held in adjusted position by frictional con-
tact with the inner side walls of the mem-
ber 58.

15 As illustrated the forward portion of each
discharge member 58 is provided with a bent
coupling 75 to which a discharge spout 77
is connected. The coupling 75 of each spout
77 is adjustable so that the inclination or
20 angle of the spout 77 with relation to the
device may be adjusted according to the
will of the operator. The forward por-
tion of each spout 77 is flared and flat-
tened, as indicated at 80, so as to more
25 efficiently spread the powder over the ad-
jacent plants and the like. Since the for-
ward portion of each discharge spout 77
is provided with a flared head or nozzle
30 80, the powder is spread over a maximum
area.

The device may be attached to one's per-
son by means of a belt 80' having an in-
termediate portion provided with an attach-
ing plate to be detachably connected to the
35 rear portion of the blower.

The device may be further secured to
one's person by means of a belt or strap

88 adapted to be passed about the shoulders
and secured to loops 89 by means of hooks
90. One section 92 of the strap 88 is pro-
40 vided with a buckle 93 by means of which
the effective length of the strap may be
varied.

When the device is arranged in front of
one's person, the operator may grip the
45 handle 94 on one side of the reservoir with
one hand and may rotate the fans and the
brushes with the other hand.

Having thus described the invention,
what is claimed as new is:

1. A valve comprising a straight casing
open at both ends and having an opening
in its upper side, an open-ended tubular
member arranged longitudinally within said
casing and having an opening in its upper
55 side adapted for registration with the open-
ing in said casing, and a radial handle con-
nected to said tubular member and extend-
ing through said casing.

2. A device of the class described com-
prising a straight tubular casing open at
both ends and having an entrance opening
in one side, an open-ended sleeve valve ar-
ranged longitudinally within said tubular
casing and having an opening in one side
60 adapted for registration with said entrance
opening, said casing being provided with
a circumferentially extending slot, at a point
remote from the entrance opening, and a
radial handle depending from said sleeve
65 valve and extending through said slot.

In testimony whereof I affix my signature.

CHARLES J. WOTIER. [L.S.]
